UNITED STATES PATENT OFFICE.

ADOLPH H. LICHTER, OF TOLEDO, OHIO, ASSIGNOR TO THE WILLYS-OVERLAND COMPANY, OF TOLEDO, OHIO, A CORPORATION OF OHIO.

UPHOLSTERING PADDING.

Application filed June 21, 1919. Serial No. 305,842.

To all whom it may concern:

Be it known that I, ADOLPH H. LICHTER, a citizen of the United States, and a resident of Toledo, in the county of Lucas and State of Ohio, have invented a certain new and useful Upholstering Padding; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

The invention relates to a padding that is used in upholstering for forming cushioned seats and backs. Special advantage is found in its use in connection with the formation of automobile seats and backs. In such cases the padding, usually formed of a cushioning material, such as cotton, hair, or similar loose fibrous material, is secured by sewing to a backing or base cloth. It is common to use a sheet of cotton cloth in order to secure the cushioning material in position so that the seat or back, or other cushion parts, may be readily formed, that is, so that the padding may be readily covered with leather, or imitation leather, and the cushion secured to the springs or other supporting parts. Sewing of the cushioning material to the backing is difficult and the material becomes entangled with the machine, if it is done by a machine. Also if there is any short fibre in the cushioning material it soon works loose and often there is a great deal lost from the cushioning material and inasmuch as the fibres of some cushioning material breaks, it distributes itself in the air and operators find it exceedingly disagreeable to handle because of breathing in of the dust and short fibres that either form or are often contained in the long fibres of the cushioning material. The covering, such as leather or imitation leather, is usually secured to the cushioning material by sewing along substantially the same lines that the cushioning material is sewed to the backing. On account of the springy nature and the looseness of the cushioning material it is quite difficult for the operators to follow the line of sewing the cushioning material to the backing when sewing the cover to the cushioning material and backing. By my invention I have provided a means whereby

these difficulties are entirely overcome. Before sewing the cushioning material to the backing the cushioning material is covered with a stretchable sheet material having more or less elasticity which will stretch over the rounded tufted upper surface that will thus be formed in the cushioning material when it is sewed to the backing. The distance between the sewing lines along the surface of the stretchable material being somewhat greater than the distance between the same lines measured along the backing, the stretchable material will readily conform to this difference and cover the cushioning material in such a way as to form defined tufts but also in such a way as to completely contain between it and the backing all broken or short fibres and all dust. Also it provides a means whereby the padding strips may be readily handled and manipulated in subsequent operations without the inconvenience to the operators that an uncovered padding material has.

For the stretchable sheet material I preferably use crêpe paper which is yieldable, exceedingly cheap, readily sewable, and being stretchable will not tear by reason of drawing it over the cushioning material in the sewing operation and moreover will not subsequently readily tear by reason of its being thus stretched and will not be readily cut by the sewing operation, such as along the holes formed by the needle. The crêpe paper is preferably placed so that the sewing lines will run substantially parallel to the wrinkles.

An article containing my invention is illustrated in the accompanying drawing, it being understood that the invention may be contained in articles of different forms. The article selected is for purposes of illustration to show a practical application of the invention.

Figure 1 of the drawing illustrates a sectional view of the padding. Fig. 2 illustrates a perspective view of a portion of the padding strip, it being understood that the padding may be sewed by gang machines and run to any length. Fig. 3 is a view of the padding having biscuit tufts.

In the drawings, 1 is the cushioning material of loose fibre, such as cotton, hair, or other loose fibrous material. 2 is the backing to which the cushioning material is to

be secured. 3 is crêpe paper having the fine wrinkles indicated somewhat conventionally at 4. The cushioning material is laid upon the backing 2 and the crêpe paper 3 is laid over the cushioning material, then the three parts are sewed together by the stitchings 5. This may be done along parallel lines, as indicated in the figure, also it may be sewed along cross lines forming 10 biscuit shaped tufts. The crêpe paper will stretch and conform to the substantially cylindrical surface in one case, or substantially spherical surface in the other case. At 6 is shown, in a conventional way, the 15 wrinkles of the crêpe paper slightly stretched or open. The showing is somewhat magnified or exaggerated in order to clearly illustrate the position or condition of the wrinkles of the crêpe paper when it has been stretched after the sewing operation and therefore showing its extensibility.

I claim:—

1. An upholstering padding having raised tufted portions consisting of a layer of loose fibrous tufting material secured by stitches between a sheet material and a freely extensible sheet material that will extend to conform to the raised portions of the upholstering padding and tufts while stitching.
2. An upholstering padding having raised tufted portions consisting of a layer of loose fibrous tufting material secured by stitches between a sheet material and a freely extensible non-woven sheet material that will extend to conform to the raised portions of the upholstering padding and tufts while stitching.
3. An upholstering padding having raised tufted portions consisting of a layer of loose fibrous tufting material secured by stitches between a sheet material and a freely extensible paper that will extend to conform

to the raised portions of the upholstering padding and tufts while stitching.

4. An upholstering padding having raised tufted portions consisting of a layer of loose fibrous tufting material secured by stitches between a sheet material and wrinkled paper that will extend to conform to the raised portions of the upholstering padding and tufts while stitching.

5. In an upholstering padding having raised tufted portions, a layer of loose fibrous material secured by stitches between a layer of fabric and a layer of crêpe paper which will conform, while stitching, to the tufted portions formed by the loose fibrous material.

6. In an upholstering padding having raised tufted portions extending parallel along the padding, a layer of loose fibrous material secured by the parallel lines of stitches between a layer of fabric and a layer of crêpe paper which conforms to the tufted portions while being stitched.

7. A pad for use together with a covering of leather or other covering material as upholstery, without other treatment or additions, which comprises a body portion of cotton, stitched with parallel rows of stitches, together with a back covering of fabric of a nature to form a permanent upholstery back, and a front covering of non-woven material, said rows of stitches being spaced to act as a guide in stitching thereto an upholstery front covering, and said pad being adapted for use in stitching machines for the mounting of said upholstery covering on the non-woven surface thereof, without presenting a perforated surface to catch in the needles of such stitching machines.

In testimony whereof, I have hereunto signed my name to this specification.

ADOLPH H. LICHTER.
